UNITED STATES PATENT OFFICE.

LILLON B. BOYCE, OF SYRACUSE, NEW YORK.

FAUCET.

1,365,369.

Specification of Letters Patent. Patented Jan. 11, 1921.

Application filed May 3, 1920. Serial No. 378,560.

To all whom it may concern:

Be it known that I, LILLON B. BOYCE, a citizen of the United States, residing at Syracuse, in the county of Onondaga and 5 State of New York, have invented certain new and useful Improvements in Faucets, of which the following is a specification.

My invention has for its object to provide a simple, inexpensively constructed 10 faucet of the type in which the valve is held closed by water pressure and the object of my invention is to eliminate some of the cost of casting, molding and buffering faucets of this type by simplifying the structure and enabling bar metal or tubing to 15 be used.

More specifically, the invention resides in those novel features of construction, combination and arrangement of parts, all of 20 which will be first fully described, then be specifically pointed out in the appended claims and illustrated in the accompanying drawing, in which:

Figure 1 is a side elevation of a faucet 25 embodying the invention.

Fig. 2 is a vertical longitudinal section of the same, the parts being in the position they assume when the faucet is open.

Fig. 3 is a view similar to Fig. 2, with 30 the parts in the closed position.

Fig. 4 is a vertical longitudinal section of the faucet body with the valve parts removed.

Fig. 5 is a vertical section showing a 35 slight modification of the structure.

In the drawing, in which like numerals indicate like parts in all of the figures, 1 represents the body which is composed of a section of rod or tubing. When composed 40 of a section of rod, the body is bored to form a longitudinal passage 2 for the valve stem 8 and is counterbored from one end as at 6 to form a socket to receive the knob piston or push plug 9 which is screwed onto 45 the valve stem 8. The body 1 is also counterbored from the opposite end to form a water passage 3 and is additionally counterbored at 4 and tapped to receive the supply water pipe 14, a portion being turned 50 out as at 5 to form a valve chamber. The body 1 is also bored and tapped at 7 at right angles to the counterbore 3 to form the outlet in which the discharge nozzle section 15 is secured.

55 The valve parts include a leather or other

similar washer 10 secured against a metallic washer 11 by a conical washer 12 which is forced against the washer 10 by the screw 13 which is tapped in the end of the stem 8.

It will be observed that the bore 7 is of 60 such diameter that the area of the passage of the discharge nozzle 15 is preferably equal or greater than the area of the counterbore 3 surrounding the stem 8, so as to reduce the pressure in the passage 13 to the extent that the water will not be forced 65 through the passages 2 and 6, it being understood that the stem 8 fits the passage 2 with a snug working fit and the piston part of the knob 9 also fits the counterbore 6 with a 70 snug working fit.

When the parts are assembled, they are as shown in Figs. 2 and 3. When pressure is not applied to the knob 9 the water pressure against the adjacent end of the valve 75 will seat the valve, as shown in Fig. 3, but when pressure is applied to the knob 9 to overcome the water pressure, the valve is unseated, as shown in Fig. 2, and the water is free to flow out.

When the faucet is made of tubing, it should, of course, be understood that the bores 2 and 3 are formed in the insert plug 16 (see Fig. 5) which plug is welded, brazed, or otherwise secured in the tubing body.

From the foregoing description, taken in connection with the accompanying drawing, it is thought the complete construction, operation and advantages of my invention will be readily understood by those skilled in the 90 art.

What I claim is:

1. A faucet comprising a rod-like body having a passage through the same, said passage comprising a valve stem guide passage, a push plug socket, a water passage, a valve chamber and a tapped bore to receive a water supply pipe, a discharge bore communicating with said water passage, a discharge nozzle screwed into said discharge 100 bore and a valve mechanism comprising a stem, a push plug and a valve proper, said valve chamber having inclined end walls and said valve proper including a coniform member on the pressure side opposite the 105 inclined wall of the valve chamber at the pressure end, substantially as shown and described.

2. A faucet comprising a rod-like body having a valve stem bore, a counterbore at 110

one end, a counterbore at the opposite end threaded to receive the water supply pipe, a valve chamber and a water passage bore together with an outlet bore tapped to receive an outlet nozzle, a valve stem operating in the stem bore, a push plug having a piston portion to operate in the first mentioned counterbore, and a valve comprising a metallic washer, a flexible washer, a second 5 metallic washer and a screw for holding said washers on the end of the valve stem,

said second metallic washer comprising a coniform body and said valve chamber having inclined end walls, the end walls at the pressure side being opposed to the coniform 15 surface of the second metallic washer and the inclined wall at the relief side of the pressure chamber constituting the valve seat, all being arranged substantially as shown and described.

LILLON B. BOYCE.
